[57] CLAIM

The ornamental design of a radio transmitter, substantially as shown.

DESCRIPTION

FIG. 1 is a perspective view of a radio transmitter showing my new design;

FIG. 2 is a top plan view of the radio transmitter of FIG. 1;

FIG. 3 is an end view of FIG. 2, as viewed from the left end thereof;

FIG. 4 is an end view of FIG. 2, as viewed from the right end thereof;

FIG. 5 is a bottom plan view of FIG. 2;

FIG. 6 is a side view of FIG. 2 as seen from either side of the said FIG. 2; and

FIG. 7 is a side view of FIG. 5 as seen from either side of the said FIG. 5.
